Primary Examiner — Catherine S Posthauer

Assistant Examiner — Amina Rahman

(57) **CLAIM**

The ornamental design for a bracelet, as shown and described.

DESCRIPTION

FIG. 1 is a front, right, and bottom perspective view of a bracelet, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a view thereof when it is laid flat and straight;

FIG. 9 is a detailed view taken from encircled portion labeled "9" in FIG. 8;

FIG. 10 is a detailed view taken from encircled portion labeled "10" in FIG. 8; and,

FIG. 11 is a detailed view taken from encircled portion labeled "11" in FIG. 8.

The broken lines in FIGS. 8, 9, 10, and 11 denote the boundaries of the detail areas and form no part of the claimed design.

1 Claim, 11 Drawing Sheets
